UNITED STATES PATENT OFFICE

2,026,695

HOOD LATCH

Norton A. Mears, Chicago, Ill., assignor to Chicago Forging & Manufacturing Co., Chicago, Ill., a corporation of Illinois

Application November 9, 1932, Serial No. 641,878

4 Claims. (Cl. 292—48)

My invention relates to an improvement in latching means for closures and, more particularly, to an improvement in means for actuating the inside hood latches of a multiple hinged automobile closure, although my invention may be applied to other closures for other mechanisms. One object is the provision of means for adequately latching an automobile hood closure where the latches and keepers have to be positioned at different levels. Another object is the provision of latching means for a hood in which the lower edge is irregularly formed. Other objects will appear from time to time in the course of the specification and claims.

15 I illustrate my invention more or less diagrammatically in the accompanying drawings, wherein—

Figure 1 is a side elevation;

Figure 2 is an inside elevation of the latching mechanism;

Figure 3 is a section on the line 3—3 of Figure 2;

Figure 4 is an inside elevation of the locking parts;

25 Figure 5 is a section on the line 5—5 of Figure 4;

Figure 6 is a view similar to Figure 4 of a variant form;

Figure 7 is a view similar in part to Figure 4, 30 with a slight variation; and

Figure 8 is a section on the line 8—8 of Figure 7. Like parts are indicated by like symbols throughout the specification and drawings.

Referring to the drawings, A indicates a portion of the automobile frame, A¹ is the radiator, A² is part of the body of the automobile, A³ and A⁴ are abutment portions connected respectively with the body A² and with the radiator A¹.

35 B generally indicates a multiple hinged hood closure having a lower edge B¹ substantially offset from the horizontal, one end of the edge as at B² being substantially lower than the opposite edge as shown at B³.

40 C is a base plate provided with bearings C¹ in which is mounted the rock shaft C². The rock shaft is provided with a central crank offset C³ and with a terminal crank offset C⁴ at one end, which terminal offset is positioned between the upper bearing loops C⁶ of the bearing supporting plate C⁵. The opposite end of the rock shaft C² rotates in a bearing bracket indicated as C¹⁶ and terminates in a latching offset or member C⁷. The plate C⁵ has lower bearing loops C⁸ in which rotates the shorter rock shaft C⁹ having

a central crank offset C¹⁰ connected as by the link C¹¹ with the crank C⁴ on the rock shaft C². The shaft C⁹ also terminates in a locking crank C¹². The locking cranks C⁷ and C¹² respectively are opposed to any suitable keepers C¹³ C¹⁴. It will be understood that owing to the connection between the crank offsets C⁴ and C¹⁰ the two rock shafts C² and C⁹ are constrained to unitary rotation.

45 In order to rotate the rock shafts and thus in order to actuate the locking members C⁷ and C¹² I provide an exterior handle D passing through the plate C and through an aperture D¹ of the hood closure. It rotates for example in the bearing D² upset in the plate C. It is provided with an inner crank D³ which is connected as by the link D⁴ with the crank C³ on the rock shaft C². The arc of rotation of the handle D and the crank D³ is limited by any suitable upset stops D⁵ which engage the extension D⁶ of the crank D³. D⁷ is any suitable nut screw-threaded to the inner portion of the handle D, whereby the entire assembly is held together. It will be realized that rotation of the handle D in one direction serves to move the locking members C⁷ and C¹² from locking into unlocking position and rotation in the other direction serves to move them from unlocking to locking position.

50 Referring to the form of Figure 6 I illustrate a variation of the device in which the rock shaft C² is provided with an offset crank C⁴ at each end and where two supplemental rock shafts C⁹ are employed instead of the single one shown in the form of Figure 1.

55 It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing.

60 In particular, I wish it to be understood that whereas I have shown the links C¹¹ as extending downwardly from the main rock shaft C² they can with equal efficiency be made to extend upwardly from an actuating shaft or one may extend down and one up.

65 The link C¹¹ is made with a double turn at the top where it engages the crank portion C⁴, the crank portion being correspondingly somewhat broadened at that point to receive it. This is important when, as in Figure 4, a structure is

used in which the crank C⁴ is in raised position when the device is in locking operation. Even if the device is subjected to considerable vibration there is no possibility of the upper eye of the link 5 C¹¹ from slipping down the sides of the crank C⁴. In other words, it keeps the device in locked position and in proper operative relation.

In the form of Figures 7 and 8 the handle D is positioned below instead of above the rock shaft 10 C². The plate C extends downwardly instead of upwardly from the rock shaft, the bearing C¹ being on the upper instead of the lower edge of the base plate C. The handle lever D³ is indicated in somewhat different form with a connector G pivoted thereto and in sliding relationship with an elongated crank offset portion C¹ of the rock shaft C². The locking position is illustrated in full line and the unlocking position in dotted line in Figure 7.

20 It will be realized that whereas I have described and shown a practical and operative device, nevertheless many changes might be made in the size, shape, number and disposition of parts without departing from the spirit of my invention. I 25 therefore wish my description and drawings to be taken as in a broad sense illustrative and diagrammatic rather than as limiting me to my specific showing.

20 The use and operation of my invention are as 30 follows:

It sometimes happens, in the employment of multiple hinge closures for automobile hoods, that the frame is offset from the horizontal, giving the lower edge of the hood an irregular 35 formation. Such a structure is shown in Figure 1. I find it in such case desirable, rather than tilting the rock shaft C², to provide an extension or a supplemental rock shaft, such as C⁹, which can be actuated, as by the link C¹¹. In the form 40 of Figure 1 a single rock shaft is employed. If the hood closure is otherwise arranged, as in case some mechanism interferes with the positioning of the handle D or if the edge is upwardly offset in the center, as in the form of Figure 6, then I 45 may find it necessary to employ a supplemental shaft C⁹ at each end of the hood, as shown in Figure 6. As above explained, the double eye or loop at the upper end of the link C¹¹ prevents it from slipping down on the crank offset C⁴, and 50 keeps the parts in proper locking relationship.

55 Referring to the form of Figures 7 and 8, as contrasted to Figures 1 and following, the handle shaft is rotatably positioned below instead of above the rock shaft, a disposition which may be advantageous for example in case the spacing of louvers or other hood openings is close. In other words, in the form of Figure 7 as contrasted to Figure 1, the handle shaft may penetrate the 60 hood at a point below the lower edges of the louvers.

I claim:

1. In an automobile hood closure having a lower edge terminating at one end at an elevation 65 appreciably above that of the opposite end to provide a long end and a short end for said closure, means for securing the lower edge of said hood in closed position comprising a latch member adjacent to the lower edge of the hood at the 70 short end thereof, a latch operating rock shaft extending inwardly of the hood from said short end, a second latch member adjacent to the lower edge of the hood at the long end thereof, a second latch operating rock shaft extending inwardly of the hood from said long end of the 75

hood, said rock shafts being operatively connected respectively to the first and second mentioned latch members, and a single latch operating means positioned on said closure intermediate said latch members, and operatively connected to both of said rock shafts. 8

2. In an automobile hood closure having a lower edge terminating at one end at an elevation appreciably above that of the opposite end to provide a long end and a short end for said closure, means for securing the lower edge of said hood in closed position comprising a latch member adjacent to the lower edge of the hood at the short end thereof, a latch operating rock shaft extending inwardly of the hood from said short end, a second latch member adjacent to the lower edge of the hood at the long end thereof, a second latch operating rock shaft extending inwardly of the hood from said long end of the hood, said rock shafts being operatively connected respectively to the first and second mentioned latch members, and a single latch operating means positioned on said closure and operatively connected to the first mentioned rock shaft intermediate the ends thereof, and a connecting link 25 between the first and second mentioned rock shafts whereby both shafts are operatively connected to the latch operating means.

3. In an automobile hood closure having a lower edge terminating at one end at an elevation appreciably above that of the opposite end to provide a long end and a short end for said closure, means for securing the lower edge of said hood in closed position comprising a latch member adjacent to the lower edge of the hood at the short end thereof, a latch operating rock shaft extending inwardly of the hood from said short end, said rock shaft being provided on its inner end with an offset portion forming a crank, a second latch member adjacent to the lower edge of the hood at the long end thereof, a second latch operating rock shaft extending inwardly of the hood from said long edge of the hood, said rock shafts being operatively connected respectively to the first and second mentioned latch members, said rock shaft being provided at its inner end with an offset portion forming a crank, the crank portions of the first and second rock shaft members being substantially in vertical alinement, and a single latch 50 operating means positioned on the closure intermediate said latch members and directly connected to one of said rock shafts, and a link connecting the cranks of said rock shafts for simultaneously actuating the latch members. 55

4. In an automobile hood closure having the lower edge terminating at one end at an elevation appreciably above that of the opposite end to provide an appreciably greater vertical dimension at the rear end than at the front end thereof, means for securing the lower edge of the closure in closed position comprising a latch member positioned adjacent the lower front corner of the hood, a latch operating rock shaft operatively associated with the latch member and extending inwardly of the hood from its forward edge, said rock shaft being provided at its inner extremity with an arcuate crank portion, a latch operating member positioned on the closure and connected directly to said rock shaft intermediate the latch and said crank portion, a second latch member positioned adjacent the lower rear corner of the closure, a second rock shaft operatively connected to said second latch member and extend- 75

ing inwardly from the rear edge of the closure, said second rock shaft being provided at its inner end with an arcuate crank portion, the crank portions of the two rock shafts being in substantial vertical alinement, a link member operatively connecting said crank portions, said link member at least one end thereof being provided with a relatively broad eye member through which one

of said arcuate link portions extends to thereby center the link with reference to the arcuate crank portion, said connecting link operating to move the second rock shaft in unison with the first rock shaft in response to operation of the latch operating member.

NORTON A. MEARS.
